UNITED STATES PATENT OFFICE.

FLOYD WILLIAM LINTON, OF ENNIS, MONTANA.

FISH GUARD.

Application filed October 28, 1924. Serial No. 746,454.

To all whom it may concern:

Be it known that I, FLOYD WILLIAM LINTON, a citizen of the United States, residing at Ennis, in the county of Madison and State of Montana, have invented a new and useful Fish Guard, of which the following is a specification.

The present invention relates to a fish guard especially designed for use at the heads of irrigating ditches to exclude fish from the irrigating ditches for obvious reasons.

An object of the invention is to provide a device of this character which will be continuously rotated by the passage of the water into the irrigating ditch, eliminating the necessity of providing electric or mechanical energy for accomplishing the rotation thereof.

Another important object of the invention is to provide a device which will insure against logs, or other foreign matter from collecting at a point adjacent to the guard to render the guard inactive.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view disclosing a guard constructed in accordance with the invention.

Figure 2 is a longitudinal sectional view through the guard.

Figure 3 is a sectional view taken on line 3—3 of Figure 2.

Figure 4 is a sectional view taken on line 4—4 of Figure 2.

Referring to the drawings in detail, the reference character 5 indicates the side walls of the guard proper, which walls may form continuations of the usual side walls of the irrigating ditch in which the guard is positioned.

Secured to the side walls 5 and extended upwardly therefrom are guiding members 6 which also act as supports for the vertically movable elongated bearing members 7 that are provided with openings to accommodate the water wheel shaft 8 on which

the water wheel 9 is mounted. These members 7 are provided with teeth 10 disposed along one edge thereof, which teeth mesh with the teeth of the pinions 11 mounted on the ends of the shaft 12, which shaft also carries a relatively large pinion 13 meshing with the worm 14 disposed at the upper end of the rod 15, the lower end of the rod 15 being supplied with an operating wheel 16 whereby the rod 15, may be rotated to move the pinion 11 to raise or lower the bearing members 7.

A gearing housing indicated at 17 is arranged adjacent to the shaft 8 in which gearing housing operates the pinion carried at one end of the shaft 8, the pinion meshing with a relatively large pinion also mounted in the gear housing and carried at one end of the shaft 19.

This shaft 19' is square in cross section and moves in the tubular shaft 20 which is formed with a relatively square bore to accommodate the shaft 19' so that rotary movement of the shaft 19' will produce a relative rotary movement of the tubular shaft 20 but at the same time permit of a sliding movement of the shaft 19' longitudinally of the tubular shaft 20 to compensate for vertical movement of the elongated bearing member 7 when it is desired to move the same longitudinally of its support to vary the depth of operation of the blades of the wheel 9. As illustrated by Figure 1 the shaft 20 is formed with a reduced portion 21 that carries a pinion not shown meshing with the relatively large pinion carried at one end of the shaft 24, on which the cylindrical guard to be hereinafter more fully described is mounted.

The cylindrical guard comprises end members 24' formed with inwardly extended flanges 25 around which the wire mesh material 26 is positioned and secured. Formed in the guarding member is a recessed portion 27 which defines a pocket throughout the length of the cylindrical guard, the depth of the pocket being sufficient to allow sticks, or other foreign matter to enter and be passed through the irrigating ditch in which the device is positioned.

Arranged adjacent to the cylindrical guard is a pivoted plate 28 which wipes the surface of the cylindrical guard in a manner to prevent material from choking the pocket or passing to a position between the bottom wall 29 of the irrigating ditch

and the guard, to retard movement of the rotary guard. Stub shafts 30 are formed at the ends of the plate 28 and are positioned in suitable openings formed in the 5 side walls of the guard proper, so that the plate may be moved with comparatively little exertion on the part of the operator.

Angularly disposed bracing bars 31 have 10 connection with the uprights 32 and 33, at the lower ends of the bars 31, while the upper ends of the bars 31 are connected with the guiding members 6 to hold the guiding members in their upright positions.

15 From the foregoing it will be seen that as water passes through the guarding member, the water contacting with the blades of the water wheel 9 causes the same to revolve, to the end that the shafts 19 and 20 20 are rotated, which in turn rotates the cylindrical guarding member through the gearing associated with the shaft 21.

Owing to the fact that the cylindrical guarding member is constantly rotating, it 25 will be seen that a certain noise in the water adjacent to the guard will be produced, to the end that the fish which may be caught in the ditch will not move sufficiently close to the guard to become caught and carried beyond the guard. 30

I claim:—

In a fish guard, a rotary cylinder formed 35 of wire mesh material, the periphery of the cylinder having an elongated depression extending from one end thereof to the other end, said depression providing a pocket, said pocket including a substantially radial wall and curved wall, and said radial wall adapted to pick up articles to carry them 40 upwardly.

In testimony that I claim the foregoing as my own, I have hereto affixed my signature.

FLOYD WILLIAM LINTON.
